SHIELD FOR MEDICINAL NEEDLES

Sylvia C. Carwile, Roanoke, Va.

Application April 2, 1945, Serial No. 586,114

4 Claims. (Cl. 128—221)

This invention relates to a shield for medicinal needles.

At the present time hypodermic needles which are used for injection of various medicines are made of small diameter, and while these needles are made of tempered steel, or other metal, they frequently bend and break off during the projection thereof into the skin. In order, therefore, to provide a means to reinforce the needle during the initial insertion, at which time the needles usually bend or break, a shield is removably mounted about the needle and is substantially shorter in length than the needle so that the point may be projected into the desired part, after which the shield may be removed without withdrawal of the inserted needle, and the latter can then be moved inwardly for the desired length thereof. The shield is formed of complementary tubular members which are spring-pressed to closed position, and include a pair of handles which, upon movement toward each other, are adapted to move the tubular members to open position so that the shield may be removed from the needle without withdrawal of the needle.

To the foregoing objects and others which may hereinafter more fully appear, the invention consists of the novel construction, combination and arrangement of parts as will be more specifically referred to and illustrated in the accompanying drawing, but it is to be understood that changes, variations, and modifications may be resorted to which fall within the scope of the invention as claimed.

In the drawing:

Figure 1 is a detail side elevation of a medical needle, having a shield mounted thereon, constructed according to an embodiment of this invention.

Figure 2 is a top plan view of the shield.

Figure 3 is a sectional view taken substantially on the line 3—3 of Figure 2.

Figure 4 is a sectional view taken on the line 4—4 of either Figure 2 or 3.

Figure 5 is a sectional view taken on the line 5—5 of Figure 4.

Referring to the drawing, the numeral 10 designates generally a hypodermic needle construction embodying a magazine 11, having secured thereto a needle 12, which is formed with a ferrule 13 at the inner or rear end thereof, which is threaded or otherwise secured to the magazine, or pump structure 11.

In order to provide a means whereby the needle 12 will be reinforced so as to prevent bending or breaking thereof as the needle is forced into the

desired part of the body, I have provided a reinforcing shield construction, which includes a pair of complementary semi-cylindrical tubular members 14 and 15. The tubular members 14 and 15 are of a length substantially shorter than the length of the needle 12, so that a substantial portion of the needle will project from the forward end of the shield. This projecting end portion of the needle is adapted to be initially injected into the body to the limit permitted by the length of the shield, and then the shield may be removed from the needle and the latter injected into the body for the desired length.

The two tubular members 14 and 15 are of like construction and are each provided at at least one of the confronting edges thereof with interlocking tongues 16 and 17, respectively. The tubular member 14 at each end thereof is also provided with outwardly extending lugs 18 and 19, and the tubular member 15 is provided with confronting lugs 20 and 21. The lugs 18 to 21 are provided so that the two tubular members may be formed out of relatively thin metal, and the interlocking edges 16 and 17 will be maintained in interlocking position and will not overlap each other. The confronting lugs limit the movement of the tubular members toward each other and prevent overlapping of the adjacent edges thereof.

The tubular member 14 is also provided at the inner or lower edge thereof with confronting lugs 22 and 23, the lug 22 being substantially longer than the lug 23. The tubular member 15 is also provided with lugs 24 and 25, which are adapted to confront the lugs 22 and 23, respectively. The long lugs 22 and 25 provide an additional reinforcing means to reinforce the tubular members against longitudinal bending.

The tubular member 14 has secured to or formed integral with the inner edge thereof an arm 26, and a handle or bar 27 is bent at an acute angle to the arm 26. The tubular member 15 has extending from the inner edge thereof an arm 28 and a bar or handle 29 disposed on an acute angle extends from the arm 28. The two handles 27 and 29 are connected together at their lower ends by a connecting member 30, which may be integral with the lower or convergent ends of the handles 27 and 29. The handles 27 and 29 are inherently biased to a position to maintain the tubular members 14 and 15 in needle encompassing position.

A coil spring 31 is disposed at the lower ends of the handles 27 and 29 and has one end 32 thereof secured as by a lug 33 to the handle 27. The other end 34 of the coil spring 31 is secured

by means of a lug 35 to the handle 29. The spring 31 provides an additional and positive means for urging the handles 27 and 29 apart and thereby maintaining the tubular members 14 and 15 in their normal needle encompassing or closed position.

In the use of this shield, the needle 12 is extended through the shield formed by the confronting tubular members 14 and 15. The spring 31 will maintain the tubular members 14 and 15 in closed position, so as to thereby provide a closed needle reinforcing tube. The provision of the interlocking tongues or corrugations 16 and 17 provide a means whereby bending strain on the needle 12 will not cause the tubular members 14 and 15 to move to an open position. The projecting end of the needle 12 which projects beyond the shield members 14 and 15 is injected into the skin and flesh and when the needle is injected to substantially the forward ends of the shield members, the shield can be quickly and easily removed from the needle by pressing the handles 27 and 29 toward each other. The tubular members will then be moved to an open position and the tubular members can be withdrawn laterally from the needle and the latter additionally injected.

It has been found that after the needle has been initially injected into the skin or flesh additional pressure on the needle will not tend to cause it to bend or break. This bending or breaking strain occurs during the initial injection of the needle, so that when the projecting portion of the needle is injected into the skin and flesh additional injection may be made without seriously bending the needle.

This shield construction can be made out of relatively thin metal, or other suitable material,

and can, therefore, be made relatively light in weight. By providing the shield out of metal it can be easily and quickly sterilized.

The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claims.

What I claim is:

1. As a new article of manufacture, a tubular shield for a hypodermic needle comprising complementary semi-cylindrical members, a pair of handles carried one by each of said members, means swingably connecting said handles together, and means engageable with said handles for constantly urging said members to closed position.

2. A new article of manufacture as set forth in claim 1, including a connecting bar connecting the outer end of a handle to an opposite member, said handles being disposed outwardly divergent position, movement of the outer ends of said handles toward each other providing for the movement of said members away from each other to open position.

3. A new article of manufacture as set forth in claim 1, wherein confronting edges of said members are formed with interlocking tongues.

4. A new article of manufacture as set forth in claim 1, including radially disposed outwardly extending lugs carried by the free edges of said members to thereby hold said members against overlapping.
